UNITED STATES PATENT OFFICE.

PATRICK J. REGAN, OF IOWA CITY, IOWA.

FENCE-MAKING MACHINE.

SPECIFICATION forming part of Letters Patent No. 527,370, dated October 9, 1894.

Application filed May 29, 1894. Serial No. 512,932. (No model.)

To all whom it may concern:

Be it known that I, PATRICK J. REGAN, a citizen of the United States, residing at Iowa City, in the county of Johnson and State of 5 Iowa, have invented a new and useful Fence-Making Machine, of which the following is a specification.

My invention relates to machines for making fences, and it has for its object to provide 10 a simple, inexpensive, and efficient mechanism for making a fence constructed of wire strands or runners and spaced cross-stays, preferably of wood, said stays being secured in place by coiling the strands or runners 15 around the same.

Further objects and advantages of my invention will appear in the following description, and the novel features thereof will be particularly pointed out in the appended 20 claims.

In the drawings:—Figure 1 is a perspective view of a fence machine embodying my invention. Fig. 2 is a face view of one of the 25 twisters. Fig. 3 is a vertical section of the same. Fig. 4 is a detail view in perspective of one of the twisting devices with the parts thereof detached.

Similar numerals of reference indicate corresponding parts in all the figures of the drawings. 30

The framework of the machine is substantially rectangular in construction having the base-timbers 1, the corner uprights 2, and the longitudinal connecting bars 3. Mounted in 35 suitable bearings 4 in the uprights at the rear end of the machine are the trunnions of a receiving drum or reel 5, provided with terminal disks 6, to prevent lateral displacement of the fence as it is reeled thereon and further provided with a ratchet-wheel 7 engaged by a dog 8, which is pivotally connected to an operating lever 9 fulcrumed upon the spindle of the drum or reel adjacent to the plane of said ratchet-wheel. This 40 lever extends to the front of the machine within reach of the operator, as hereinafter more fully explained. Mounted in bearings 10 in the upper side beams 3 of the framework are trunnions of the direction-rolls 11 and 12, over which the fence passes upon its way from the twisting mechanism herein-after described to the receiving drum or reel. 45

The twisting mechanism comprises a series of standards 13, upon which adjacent to their extremities are mounted twisting wheels 14 55 having stationary central cores 15, which are secured permanently to the standards and rotary portions or rings 16, which are mounted upon said cores and are rabbeted, as shown at 17, to receive the peripheral flanges 18 of 60 the cores to prevent accidental displacement. The cores are provided with radial slots or kerfs 19, which register with corresponding slots 20 in the upper ends of the standards, and the rotary portions or rings of the twisting-wheels are provided with corresponding 65 radial slots 21, which are adapted to register with the slots or kerfs 19.

The twisting-wheels are provided with peripheral gear teeth 22, with which mesh the 70 teeth of intermediate gears which convey motion to the said twisting wheels from the driving-pinions 24. These driving pinions are fixed to a power-shaft 25 provided at one end with a sprocket-wheel 26, connected by a 75 chain 27 with a similar sprocket-wheel 28, which is fixed to the crank-shaft 29. The crank-shaft is provided with an operating-handle or crank 30 which is arranged upon that side of the machine adjacent to the 80 front end of the operating lever 9, whereby a single operator is enabled to control both the twisting mechanism and the reeling devices.

Secured to the rotary members or rings of the twisting wheels are radial arms 31, which 85 extend outward beyond the peripheries of the wheels, having bearing-studs 32, upon which are mounted the wire spools 38. The outer extremities of these bearing-studs are threaded, as shown at 33, for the reception of 90 tension nuts 34, which fit in recesses or cavities 35 in the outer surfaces or faces of the spools, and are thus flush at their outer sides with said surfaces of the spools. Secured to the inner ends or portions of the radial arms 95 31 adjacent to the annular portions of the twisting wheels are the curved wire-guides 36.

The strands or runners 37, as shown clearly in Fig. 1, are supplied respectively from the spools 38, and after passing around the wire-guides at the inner ends of the spool-carrying arms extend upward to and around the direction-roll 12, thence horizontally and over the direction-roll 11, and then downward to the 100

receiving-drum or reel 5; and in operation the cross-stays or pickets 39 are inserted in the radial slots or kerfs of the stationary portions or cores of the twisting-wheels, as shown in Fig. 1, and the crank 30 is operated to cause the rotation of the movable or annular portions of the twisting-wheels, thus carrying said wire-spools around the stationary portions or cores of the wheels, and also around the cross-stays or pickets. This coils or wraps each strand or runner around the cross-stay or picket, while the latter is held firmly in place in the radial slot or kerf of the core, and when the corresponding radial slots 21 of the twisting-wheels come into registration with the slots or kerfs in which the stay or picket is arranged the latter may be withdrawn radially by operating the receiving drum or reel through the lever 9.

It will be understood that one or more turns of the strands or runners around each stay or picket may be made, and that any desired number of twisting-devices may be employed according to the preferred number of strands or runners in the fence, and the stays or pickets may be spaced at intervals to suit the purpose for which the fence is designed. It will be understood, moreover, that various changes in the form, proportion, and the minor details of construction may be resorted to without departing from the spirit of the invention or sacrificing any of the advantages thereof.

Having described my invention, what I claim is—

1. In a fence machine, the combination with a suitable receiving drum or reel, and

direction-rolls for guiding the finished fence thereto, of twisting-devices having twisting-wheels comprising centrally fixed cores provided with radial slots or kerfs, and rotatable members or rings mounted upon the peripheries of said cores and having corresponding radial slots to register with the slots or kerfs in the cores, wire-spools carried by the rotatable members or rings of the twisting-wheels, wire-guides, and operating mechanism for driving the twisting-devices, substantially as specified.

2. In a fence machine, the combination with a receiving drum or reel and means for operating the same, and direction rolls for guiding the finished fence thereto, of twisting-devices comprising standards provided at their upper ends with slots, cores fixed to the standards and provided with corresponding radial slots or kerfs, rings rotatably mounted upon the peripheries of the cores and provided with radial slots to register with the slots or kerfs in the cores, radial arms connected to and carried by the rotary rings, wire-spools mounted upon the radial arms, means for adjusting the tension of said spools, a power-shaft operatively connected with the said rings, and means for operating the power-shaft, substantially as specified.

In testimony that I claim the foregoing as my own I have hereto affixed my signature in the presence of two witnesses.

PATRICK J. REGAN.
